Patented Mar. 30, 1920.

Edward Lippert

INVENTOR

BY
Richard B. O'Brien,
ATTORNEY

UNITED STATES PATENT OFFICE.

EDWARD LIPPERT, OF NEW YORK, N. Y.

TOOTH BRUSH AND PASTE HOLDER.

1,335,250.

Specification of Letters Patent. Patented Mar. 30, 1920.

Application filed September 4, 1919. Serial No. 321,636.

To all whom it may concern:

Be it known that I, EDWARD LIPPERT, a citizen of the United States, residing at New York city, in the county of New York and 5 State of New York, have invented certain new and useful Improvements in Tooth Brush and Paste Holders, of which the following is a specification.

This invention has relation to household 10 articles, with particular reference to a device for supporting a tooth brush and a device for supporting a collapsible container of tooth paste or the like.

In addition to the foregoing, this invention 15 comprehends improvements in the details of construction and arrangement of parts to be hereinafter described and particularly set forth in the appended claim.

In the accompanying drawings in which 20 similar and corresponding parts are designated by the same characters of reference throughout the several views in which they appear—

Figure 1 is a view in perspective of my 25 invention and

Fig. 2 is a transverse section taken therethrough.

Fig. 3 is a fragmentary view in front elevation of a modified form of my invention, 30 and

Fig. 4 is a view in horizontal section taken to the form shown in the immediate preceding figure.

With reference to the drawings, 10 indicates generally the base which is in the form of a strand of wire bent to form substantially parallel portions 11 and 12 connected at the end, at which points loops 13 are formed to permit fasteners or the like to be 15 inserted therethrough for securing the device to a wall. One terminal of the strand is bent laterally as at 14 and formed into a loop 15 through which the handle of a tooth brush may be inserted, the extremity of said 20 terminal contacting with the opposite extremity of the strand of wire, the extremities being soldered or otherwise secured together if desired. Connecting the parallel portions 11 and 12 adjacent the upper end 25 of the device is a pair of wires 16 in spaced relation which are formed by taking a single strand of wire and twisting the intermediate portion about the member 11 of the device,

and then lapping the extremities of the wire about the member 12 of the base portion. A 55 container 17 of a collapsible nature adapted to contain tooth paste is then inserted by means of its bottom portion between the section 16 and wrapped about one of said sections so that the tube may be moved outward 60 at right angles to the wall to permit a portion of its contents to be ejected upon the brush. Thus it will be seen that I have provided a novel form of device which is adapted to support two articles used in conjunction in such a manner as to permit access to either one without difficulty and to furthermore retain them in a cleanly and sanitary condition. Other uses and advantages will readily occur to those as they become familiar with its use. 70

While I have illustrated and described my invention with some degree of particularity, I realize that in practice various alterations therein may be made. I therefore reserve 75 the right and privilege of changing the form of the details of construction or otherwise altering the arrangement of the correlated parts without departing from the spirit of the invention or the scope of the appended 80 claim.

I have illustrated in Figs. 3 and 4 a modified form of my invention in which the tube of paste is held by means of a device consisting of a strip of metal 17 having its ends 85 bent around the members 11 and 12 of the base and a slot 18 formed therein. The lower portion of the strip is offset thus permitting the end of the tube to be readily inserted in the slot 18 in the manner described 90 above.

Having thus described my invention, what I claim as new and desire to secure by United States Letters Patent is:

A device of the character described comprising a substantially rectangular frame of wire having both end portions twisted to form a loop, and one side member twisted to form a third loop to receive a tooth brush, and means connecting the side members to 100 form a support for a tube of tooth paste.

In testimony whereof I affix my signature in presence of a witness.

EDWARD LIPPERT. [L. S.]

Witness:

Wm. Zeaman.
